UNITED STATES PATENT OFFICE.

CARL E. BAUER, OF HAMMOND, INDIANA, ASSIGNOR TO AMERICAN STEEL FOUNDRIES, OF NEW YORK, N. Y., A CORPORATION OF NEW JERSEY.

SPRING-DAMPENER.

1,140,101.

Specification of Letters Patent.

Patented May 18, 1915.

Application filed March 1, 1915. Serial No. 11,259.

To all whom it may concern:

Be it known that I, CARL E. BAUER, a citizen of the United States, residing at Hammond, in the county of Lake and State 5 of Indiana, have invented certain new and useful Improvements in Spring-Dampeners, of which the following is a specification.

My invention relates to springs, and has particular reference to a novel spring controller or dampener.

It has been found, particularly in the railway art, that coil springs used under railway cars are much more efficient and have greater capacity if a dampener, or other 15 friction inducing element, be used in connection therewith. I am aware that many such devices have heretofore been proposed, but some, or all of these, have inherent defects which are sought to be overcome in the 20 present device.

An object in the construction of an efficient spring dampener should be to provide a comparatively large friction surface in order that the friction developed in service 25 may be spread over a large area. If this is not done the engaging parts rapidly become worn and the efficiency of the device rapidly decreases.

An object in the present device is to provide two elements having portions which interengage, these portions, when assembled, inclosing the nest of springs, the two parts moving relatively to each other as the springs are actuated. The interengaging 35 portions of each part are given an initial set prior to assembling, and the initial set of each part is oppositely disposed with relation to the part it is to engage. Thus, when the parts are assembled, each thereof 40 must be deflected in order to be brought into proper position, the result being that there is an extended friction surface in engagement at all times, this surface not being limited to points or lines which rapidly become worn.

The invention will more readily be understood by reference to the accompanying drawing, wherein—

Figure 1 is a perspective view of a spring 50 dampener assembled ready for use, Fig. 2 is a similar view showing the parts as they are shaped prior to assembling, Fig. 3 is a section on the line 3—3 of Fig. 1, Fig. 4 is a view similar to Fig. 1, showing a slightly

modified form, and Fig. 5 is a view similar 55 to Fig. 2.

Referring more particularly to the drawings, it will be seen that I provide upper and lower plates 10, 11 respectively, each of said plates having end portions 12, 13 bent at 60 right angles to the plane of the plates. The end portions 12 are provided with marginal inturned flanges 14, so arranged as to coöperate with the end portion 13, and securely hold the same against lateral 65 placement. As best shown in Fig. 2, the end portions 12, 13 are given an initial bend or set, and that the bend of one section is opposite to that of its mating section. Thus, in order to assemble the parts, as shown in 70 Figs. 1 and 3, the plates must be forced into a straight line, and thereafter the ends 13 will be readily accommodated within the flanges 14. However, the tendency of the parts is to assume the position given them 75 by the initial set, thus binding the adjacent plates in close relation. When assembled, as shown in Figs. 1 and 3, the plates lie in close engagement and the friction surface is relatively great.

In the construction shown in Figs. 4 and 5 the same principle is involved. In that form the top and bottom members 15, 16 are substantially duplicates of each other, the angularly bent end portions thereof consisting of a plurality of tongues 17, 18, each of which is offset or bent out of the plane of the adjacent tongue and oppositely bent with relation to the tongue which is to engage therewith on the adjacent section. 85 After the parts are engaged, as shown in Fig. 4, the tongues have a large bearing area, although each tongue has a tendency to be brought into closer engagement with its mating tongue, due to the initial set given 90 to the parts when they are formed. Of course, it will be understood that the metal from which these dampeners are constructed will be of such quality as to maintain the initial set.

It is obvious that the constructions shown are typical only of other forms which the invention might assume, and I do not, therefore, wish to be limited to the exact forms shown and described.

I claim:

1. In a spring controller, the combination of upper and lower inclosing members, each

of said members being provided with end portions adapted to interengage and interlock with an adjacent end portion, said end portions being initially distorted, whereby 5 the parts normally tend to be brought into close frictional engagement, substantially as described.

2. In a spring dampener, the combination of a pair of plates having ends bent at right 10 angles to the plates and adapted to interengage with each other, interlocking devices on said end portions, adjacent end portions being oppositely bent with relation to a transverse plane passing through said plates 15 whereby said portions, after having been assembled, tend to separate from each other and thereby cause frictional contact, substantially as described.

3. In a spring controller, the combination 20 of a pair of inclosing members having interlocking side portions, the side portions of one member being initially formed with a concave set and the corresponding portion of the opposed member being given an initial 25 convex set, substantially as described.

4. In a spring controller, the combination of a pair of U-shaped members, the ends of which are adapted to interlock and permit relative movement between the members, an end portion of one member being formed 30 with an initial distortion with relation to the end portion with which it coöperates, substantially as described.

5. In a spring dampener, the combination of upper and lower U-shaped members 35 adapted, when assembled, to accommodate a nest of springs therebetween, the engaging portions of one member being given an initial curve with relation to the portion engaged thereby, whereby one of said engaging portions must be bent in order to accomplish such engagement, substantially as described.

In testimony whereof I have hereunto signed my name in the presence of two sub- 45 scribing witnesses.

CARL E. BAUER.
